Patented May 16, 1916.

UNITED STATES PATENT OFFICE.

WILLIAM REED-LETHBRIDGE, OF WELLINGTON, NEW ZEALAND.

ELECTRICAL FLASHER.

1,183,590.

Specification of Letters Patent.

Patented May 16, 1916.

Application filed July 22, 1915. Serial No. 41,326.

To all whom it may concern:

Be it known that I, WILLIAM REED-LETHBRIDGE, a subject of the King of Great Britain and Ireland, residing at No. 10 Hawker street, in the city of Wellington, in the Dominion of New Zealand, have invented a new and useful Improvement in Electrical Flashers; and I do hereby declare the following to be a full, clear, and exact description of the same.

This invention relates to electrical flashers and provides an apparatus whereby two sets of lamps or other electrical units are alternately illuminated or energized.

15 In carrying out the invention a single flasher which may be of ordinary construction is employed to control the circuit to one set of lamps while the circuit to a second set of lamps passes through a pivoted member which breaks the circuit to the second set of lamps when the first set of lamps is in circuit and which is operated by an electro-magnet which is energized when the circuit is passing to the first set of lamps.

25 The invention will be fully described with the aid of the accompanying drawings wherein:

Figure 1 is a plan of the device. Fig. 2 is an inverted plan of the electromagnet. Fig. 3 is a sectional plan of the electro-magnet. Fig. 4 is a side elevation of the electro-magnet. Fig. 5 is a section of a detail. Fig. 6 is a diagrammatical view showing the electrical circuits.

35 Referring to the drawings a single flasher 1 of ordinary construction is mounted upon a non-conductive base 2. The flasher 1 comprises the usual hollow tube 3 fixed at one end to a terminal 4 and provided at its other end with a contact 5. The resistance coil 27 is insulated from the tube but is in contact at one end with the terminal 4 while its other end is connected to a terminal 6 having a contact 7.

45 Two reels of non-conductive material 8 and 9 wound to form solenoids 10 and 11 are fixed upon iron cores 12 and 13 supported in brackets 14 and 15 which are fixed to the base 2. The other ends of the cores 50 12 and 13 are fixed to a plate 16 by means of set screws 17 (see Figs. 4 and 5). Below the plate 16 is a block of insulating material 18 to the underside of which are fixed two members 19 and 20. The block 18 is fixed 55 to the plate 16 as shown in Fig. 5. The end 21 of the solenoid coil 10 is fixed to the end

of the member 19 and the end 22 of the solenoid coil 11 is fixed to the end of the member 20 as shown in Fig. 2. The opposite ends of the solenoid coils are joined together as indicated at 23 in Fig. 2.

In the plate 16 a horizontal contact member 24 is pivoted on pins 25 and has a vertical member 26 of iron. A pin 47 prevents the member 26 coming into actual contact with the ends of the iron cores 12 and 13. The front end of the horizontal member 24 is provided with a contact 28 adapted to make contact with a vertical pillar 29 fixed in the base 2.

70 The wires from the circuit lead to terminals 30 and 31 upon the base 2. A wire 32 leads from the terminal 30 to a terminal 33 upon the bracket 14 while a wire 34 leads from this terminal to the end of the member 19. A wire 35 connects the pillar 29 to a terminal 36. The member 20 is connected to the terminal 4 by a wire 37 while the terminal 6 has a wire 38 leading to a terminal 39. The terminal 31 may also be connected to a terminal 40 by means of a wire 41. The two sets of wires 42 and 43 from the two sets of lamps 44 and 45 are then connected to their respective terminals 36, 39 and 40.

75 In Fig. 6 the diagram of the circuit is shown all details of construction being omitted.

The current passes from the terminal 30 to the terminal 33 thence along the bracket 14 to the core 12 and thus to the plate 16 90 and core 13. From the plate 16 it passes along the member 24 to the pillar 29 and thence along the wire 35 to the terminal 36 and lamps 44, returning by the wire 41 to the terminal 31. At the same time that the lamps 44 are in circuit electricity will be passing through the solenoids to the resistance 27 of the flasher 1 and to the lamps 45 but since the resistance 27 is of fine iron wire and closely wound not sufficient current will pass through it to affect the lamps 45. Nor is the current sufficient to energize the solenoids to enable them to attract the member 26 of the member 24 and so break the contact to the pillar 29.

10. Electricity, however, passing to the resistance 27 warms the tube 3 sufficiently to expand it and so bring the contacts 5 and 7 together thereby providing a shunt path of less resistance to receive the greater portion of the current, a portion of which, however, still continues to pass through the

resistance 27. Immediately this occurs a full load of electricity will pass through the coils of the solenoids 10 and 11 energizing them and drawing the member 26 toward them and thus breaking the contact between the member 24 and the pillar 29. The circuit is now along the wire 34 to the member 19 then to the solenoid coils 10 and 11 and member 20 and thus to the lamps 45 through 10 the medium of the wire 37, flasher 1 and wire 38. Since most of the current now flows from the terminal 4 to the terminal 6 and short circuiting the flasher, the tube 3, with less current passing through the resistance 27, will cool and contracting break the contact between the points 5 and 7 and thus extinguish the lamps 45 and again allow the current to pass to the lamps 44.

What I claim is:—

20 1. In an electric flasher of the class described, a set of lamps, a single flasher controlling the circuit to said set of lamps, a second set of lamps, an electro-magnet, a pivoted member, a circuit passing through 25 said pivoted member to said second set of lamps, said pivoted member adapted to make and break the said circuit to said second set of lamps, the circuit to said first set of lamps passing through the coils of said 30 electro-magnet and adapted to fully ener-

gize said electro-magnet when the full current passes through said single flasher and so break the circuit to said second set of lamps, substantially as set forth.

2. In an electric flasher of the class de- 35 scribed, a set of lamps, a single flasher controlling the circuit to said set of lamps, a second set of lamps, an electro-magnet, a pivoted member coöperating with said elec- 40 tro-magnet, a current passing through the cores of said electro-magnet, and through said pivoted member to said second set of lamps, said current to said second set of lamps being broken when said electro-mag- 45 net is fully energized, the circuit to said first set of lamps first passing through the coils of said electro-magnet and adapted to fully energize said electro-magnet when the full current passes through said single flasher, and so break the circuit of said sec- 50 ond set of lamps by means of the pivoted member, substantially as set forth.

In testimony whereof, I have signed my name to this specification in the presence of two subscribing witnesses.

WILLIAM REED-LETHBRIDGE.
